UNITED STATES PATENT OFFICE.

ROBERT S. GOULD, OF EAST ORANGE, NEW JERSEY.

CURTAIN-POLE ANGLE-JOINT.

SPECIFICATION forming part of Letters Patent No. 366,771, dated July 19, 1887.

Application filed January 3, 1887. Serial No. 223,163. (No model.)

To all whom it may concern:

Be it known that I, ROBERT S. GOULD, of East Orange, in the county of Essex and State of New Jersey, have invented certain new and 5 useful Improvements in Curtain-Pole Angle-Joints, of which the following is a specification.

This invention relates to an angle-joint for curtain-poles, which presents a neat and ornamental appearance, as it can be arranged in keeping with the ends of the curtain-poles, the construction being simple and so arranged that the poles can be conveniently inserted into the caps of the joint without the use of screws.

15 In the accompanying drawings, Figure 1 represents a plan of my improved curtain-pole angle-joint; and Fig. 2 is a horizontal section of the same, shown with the caps and poles placed in line.

20 Similar letters of reference indicate corresponding parts.

This improved angle-joint for curtain-poles comprises two caps, A, adapted to be slipped over the adjacent ends of the poles to be 25 coupled. Arc-shaped clips *a* are attached at their inner ends to the caps A at diametrically-opposite points and overlap at their outer meeting ends. An ornamental hollow body, B, is interposed between the ends of the poles 30 and inclosed by the arc-shaped arms. This hollow body is divided into two parts or members, one of which is slightly larger than the other, the larger segment having a lip or flange which shuts over the smaller one. Pivot-

35 screws *b* are passed through the overlapping ends of the arc-shaped clips and through the shell B, nuts *b'* being attached to the pivot-screws at their inner ends within said body.

In assembling the parts the larger segment of 40 the body B is first placed in position and the pivot-screws passed through the arc-shaped

clips into said segments, and the nuts placed over the ends of the screws. The smaller segment of the body B is then placed in position and its edge inserted within the flange of the 45 larger segment. The hollow body B conforms in shape to the pole ends, being spherical when the pole ends are spherical.

The poles may be readily adjusted by the joint at any suitable angle toward each other, 50 they being supported on brackets, as customary in curtain-pole angle-joints. The angle-joint requires no screws of any kind to attach it to the poles, the caps being simply slipped over the pole ends. It can also be used with 55 poles of different diameters, whereby a smaller number of sizes of angle-joints are required to be kept in stock.

Having thus described my invention, I claim as new and desire to secure by Letters Patent— 60

A curtain-pole angle-joint consisting of caps for inclosing the pole ends, arc-shaped clips attached at their inner ends to said caps at diametrically-opposite points, the clips of one cap overlapping the clips of the other cap at 65 their meeting points, a hollow body divided into separable segments interposed between the ends of the poles and inclosed by said arc-shaped clips, pivot-screws passed through the overlapping ends of said clips and through 70 the shell of the larger segment of said body, and nuts screwed to the inner ends of said pivot-screws within said body, substantially as described.

In testimony that I claim the foregoing as 75 my invention I have signed my name in presence of two subscribing witnesses.

ROBT. S. GOULD.
